LENO FABRIC

Burton S. Woodward, Westerly, R. I., assignor to
Delite Fabrics, Inc., a corporation of Rhode Is-
land

Application June 5, 1941, Serial No. 396,666

5 Claims. (Cl. 139—419)

This invention relates to improvements in woven elastic textile fabrics, more particularly of the so-called "leno" type weave and the method of weaving the same.

In the weaving of elastic leno fabrics, a certain group of warps are placed in each dent of the reed and there may consist of a plurality of ground warps and a leno warp in each of such dents. It is usual in the manipulation of the leno warp or crossing warp that this warp will cross a single large rubber warp where such is provided as the only ground warp in a dent; or, if a group of smaller rubber warps are provided in each dent, the leno warp will cross all of these warps, and in so crossing the entire group of rubber warps in the dent will bind the rubber warps together, and in either case a relatively thick fabric will be produced. Also, a fabric so closely woven would not possess the porosity or openings desired where the yarns used are elastic and contract when the fabric comes from the loom.

One of the objects of this invention is to provide a leno woven elastic fabric which will be thin relative to the weight of the elastic yarn provided therein.

Another object of the invention is to provide a fabric which will have a greater porosity or a larger number of openings than fabrics which have been heretofore woven with the same elastic properties.

More specifically, an object of the invention is to restrict the individual elastic warps of a group in their contraction by the crossing of a non-elastic leno warp with the individual elastic ground warps.

With these and other objects in view, the invention consists of certain novel features of construction, as will be more fully described, and particularly pointed out in the appended claims.

In the accompanying drawing:

Fig. 1 is a diagrammatic view showing one form of weave embodying my invention;

Fig. 2 is a diagrammatic view showing another form of weave embodying my invention; and

Figs. 3 and 4 illustrate diagrammatically still other forms of weaves, each embodying my invention.

In carrying out this invention, in order to produce a thinner fabric I use a group of elastic ground warps in each dent which would together make up the same count as a single elastic warp heretofore used, and I manipulate with this group in each dent to combine therewith a non-elastic warp also in the same dent by crossing the individual elastic ground warps or a smaller number of the ground warps of a group, rather than crossing the entire group at one time by which arrangement I reduce the thickness of the fabric; and also by the crossing of the individual

elastic ground warps of the group, I restrict the contraction and obtain a greater porosity of the fabric than heretofore. The crossing leno warp is bound in or combined with the ground warps at each pick of the weft in a known manner.

The number of warps in each group and their order of crossing by the leno warp at each crossing of warps may vary according to the design of the fabric desired. Each crossing of warps may include only a single ground warp of the group; or, the crossing may include pairs of ground warps at each crossing or may be any number less than the whole. However, the less number of ground warps crossed at each crossing of warps, the thinner the finished fabric and the more securely locked in place are the leno warps.

Referring to the drawing for a more detailed description of the invention, in which Fig. 1 illustrates diagrammatically a fabric in stretched condition, 10 designates the elastic ground warps under tension which may consist of covered or uncovered rubber strands or like substance which have sufficient inherent elasticity to be stretchable and returnable to normal position. These elastic ground warps are arranged two in a group or in one dent of the reed designated A and operate with a non-elastic leno or crossing warp 11 also in the same dent of the reed. The wefts, designated generally 12, with which the warps interlace, may be all elastic or non-elastic or a combination of both and are here shown as consisting of an elastic weft 13 and non-elastic weft 14, alternating at each pick or in groups of two picks. However, this particular order may be varied to suit the particular result desired

In the fabric diagram of Fig. 1 the leno or crossing warp 11 operated by its doup crosses the elastic warp 15 for three picks and the other elastic warp 16 of the group 15, 16 is raised to float across the wefts which lock with the companion warp of the group. For the successive three picks the leno or crossing warp 11 is operated to cross the other elastic warp 16 of the group 15, 16 and the now free elastic warp 15 is raised to float across the wefts which lock with the companion warp of the group. For the next successive three picks the leno warp 11 is again crossed or combined with the ground elastic warp 15 and the now free ground warp 16 is floated across the such wefts as heretofore. This completes a repeat of the design. It will be apparent that in this arrangement the non-elastic leno or crossing warp is interlocked with each individual elastic warp of the group with which it is associated, which provides a firm tying of the leno warp in the fabric.

In Fig. 2 of the drawing, the group B of ground warps comprises three elastic threads 17, 18, and 19 in each group under tension and to function with a non-elastic leno warp 20 all in the same dent of the reed. As in the diagram shown in

Fig. 1, the wefts in this arrangement also consist of a non-elastic weft 21 and elastic weft 22 alternating at each pick with one another to interlace with the warps. In the arrangement of the crossing of warps in this instance, the leno warp 20 is first crossed back and forth for three picks to combine with the ground warp 17; then it crosses warp 18 back and forth for two picks to combine with the ground warp 18, and then crosses warp 19 back and forth for three picks to combine with ground warp 19, and then combines with the warp 18 for two picks and combines with warp 17 for three picks for the start of another repeat of the weave. The portions of the warps in each group of ground warps which have not been crossed by the leno thread are interwoven with the wefts. The ground plan of weave here shown in the diagram is not any particular plan of weave but merely one to conveniently tie the uncrossed portion of the ground warp with the wefts.

In Figs. 3 and 4, I have shown further application of the invention. In Fig. 3, the group C of ground warps comprises four elastic threads 23, 24, 25, and 26, with a non-elastic leno warp 27 all in the same reed dent. The wefts in the instant disclosure may also comprise an elastic weft 28 alternating at each pick with a non-elastic weft 29. In this diagram, the leno warp is shown as beginning a repeat by first crossing back and forth for three picks with a single ground warp of the group, then crossing back and forth with a pair of ground warps for two picks, then a single ground warp on the other side for three picks, and then in the reverse order back to ground warp 23 to complete a repeat of the weave.

In Fig. 4 there are three elastic ground warps 30, 31, and 32 and one crossing or leno warp 33 in each dent, and here the leno warp 33 crosses the pair of ground warps 30 and 31 for three picks and then shifts and crosses the pair of ground warps 31 and 32 for three picks, and then shifts back to cross the pair of ground warps 30 and 31 to commence another repeat.

In each of the above constructions the group of smaller warps in each dent is spread out to cover a broader or wider area of less thickness than previously.

In Figs. 1 and 2, I have shown the ground warps arranged in groups and positioned side by side. However, it may be desirable in some design of fabric to combine this particular grouping and crossing of warps so that each group of leno woven warps will be spaced from each other by warps which only interlace with only the wefts. The ground plan of the weave may be any suitable weave that may be combined with the particular grouping of ground elastic warps and the order of crossing with the non-elastic leno warp combined therewith.

By combining the leno warp with single or individual warps, as in Figs. 1 and 2, the warps are not bunched to form a thick fabric, and the porosity of the fabric is increased. However, where the warps are of small diameter, this may even be accomplished where the crossing is of more than one of the warps of the group.

In substituting a group of ground elastic warps of a combined count equal to a single elastic ground warp of a count of sufficient dimension to provide a fabric having the degree of resistance to stretch desired and crossing the individual

ground elastic warps with the non-elastic leno warp in the manner herein disclosed, I am able to produce beautiful and attractive lace-like fabric, smooth of surface, relatively thin, and having the required resistance to stretch desired.

I claim:

1. An elastic leno woven fabric consisting essentially of filling threads combined in woven relation with elastic ground warps and non-elastic leno warps and in which a group of said elastic ground warps are combined with a non-elastic leno warp of said leno warps and in which there is a crossing of more than one but less than the whole group of the said elastic ground warps by the leno warp at each crossing of the warps and in which such crossing of warps occurs until all the warps of said group have been crossed by the said leno warp in each repeat of weave.

2. An elastic leno woven fabric consisting essentially of filling threads combined in woven relation with elastic ground warps and non-elastic leno warps and in which a group of said elastic ground warps are combined with a non-elastic leno warp of said leno warps and in which there is a crossing of only a portion of said group of elastic ground warps by the leno warp at each crossing of warps and in which such crossing of warps occurs only in pairs and until all the warps of the said group of ground warps have been crossed by the said leno warp in each repeat of weave.

3. An elastic leno woven fabric consisting essentially of all elastic ground warps divided in groups equally spaced from each other and combined in woven relation with filling threads and non-elastic leno warps and in which each of said groups of elastic ground warps are combined with one of said non-elastic leno warps, and in which there is a crossing of a number of the warps of said group less than the whole thereof by said leno warp at each crossing of warps and in which such crossing of warps occurs until all of said group have been crossed by said leno warp in each repeat of weave.

4. An elastic leno woven fabric consisting essentially of all elastic ground warps divided in groups equally spaced from each other and combined in woven relation with filling threads and non-elastic leno warps and in which each of said groups of elastic ground warps are combined with one of said non-elastic leno warps and in which there is a crossing of only individual warps of said group of elastic ground warps by the leno warp at each crossing of warps and in which such crossing of warps occurs until all of said group have been crossed by said leno warp in each repeat of weave.

5. An elastic leno woven fabric consisting essentially of all elastic ground warps divided in groups equally spaced from each other and combined in woven relation with filling threads and non-elastic leno warps and in which each of said groups of elastic ground warps are combined with one of said non-elastic leno warps and in which there is a crossing of less than the total number of warps of said group of elastic ground warps by the leno warp at each pick and in which such crossing of warps occurs until all of the warps of said group have been crossed by said leno warp for each repeat of weave.
